W. C. COLLIGNON

SPEED GOVERNOR FOR PNEUMATIC MOTORS

Filed Feb. 14, 1921

Patented July 3, 1923.

1,460,705

UNITED STATES PATENT OFFICE.

WILLIAM C. COLLIGNON, OF CHICAGO, ILLINOIS.

SPEED GOVERNOR FOR PNEUMATIC MOTORS.

Application filed February 14, 1921. Serial No. 444,686.

To all whom it may concern:

Be it known that I, WILLIAM C. COLLIGNON, a citizen of the United States, residing at Chicago, in the county of Cook and State 5 of Illinois, have invented certain new and useful Improvements in Speed Governors for Pneumatic Motors, of which the following is a specification.

The invention relates to speed governors 10 for pneumatic motors.

One of the objects of the invention is to provide an improved speed governor for pneumatic motors.

Another object is to provide an improved 15 speed governor for pneumatic motors especially adapted for use in connection with piano players.

Another object is to simplify the structure and to render it more effective and 20 durable.

Other, further and more specific objects 25 of the invention will become readily apparent, to persons skilled in the art, from a consideration of the following description, when taken in conjunction with the drawings, wherein:—

Fig. 1 is a section taken on line 1—1 of Fig. 2.

Fig. 2 is a section taken on line 2—2 of 30 Fig. 1.

Fig. 3 is a section taken on line 3—3 of Fig. 2.

Fig. 4 is a section taken on line 4—4 of Fig. 3.

In all the views the same reference characters are employed to indicate similar 35 parts.

The governor, in use, is placed in the air conduit between an air pump and the motor 40 in a piano player and is provided with automatic means to maintain constant speed of the motor under large variations of air velocity.

It is also provided with manual means 45 for varying the speed of the motor, the automatic means serving to maintain constant speed set by the manual means, and adjustable means at which the constant speed may be increased or diminished.

There is also provided in the governor a 50 by-pass around the path that includes the automatic means, whereby manual adjustment may be made to operate the motor at full speed without changing the adjustment 55 of the automatic means.

In the particular embodiment illustrated

5 is a casing containing a valve chamber 6 and opening therefrom are two passageways, or air conduits, 7 and 8. A valve 9 is slidable to close the opening 8. The rear 60 end 10 of the valve 9 is provided with a tapering slot 11 so that the passageway 8 may be gradually opened thereby by use of the sliding manually operated rod 12. Rising from the body portion of the valve 9 is a 65 stem 13 having a slot 14 with which the angularly disposed end 15 of the rod 12 engages. To open the passageway 8, by means of the valve 9, the rod 12 is moved in the direction of the arrow 16, and to close the 70 passageway it is moved in the opposite direction.

A lift valve 17 is hinged at 18 and normally closes the passageway or air conduit 7. A rod 19 passes thru a stem 20 on the 75 valve 17 and is provided with an upturned end 21 which engages the stem 20 to raise the valve by operation of the rod 19.

Below the casing 5 is a plate 22 which has 80 openings 23 and 24 to correspond with the openings 7 and 8 in the casing 5. Below the plate 22 is a bellows structure or pneumatic action 25, enclosing a chamber 26 which is in controlled communication with the chamber 6 by means of the passageways 7 and 8. 85

A pressure responsive member 27 operated by movement of the diaphragm 27' is hinged as at 28 to a support 29 through an opening 30 in which a valve lever 31 is vertically movable. The rear end of the 90 valve lever 31 is connected to the pressure responsive member 27, at 32. The chamber 26, of the pneumatic action, is connected to the passageway 7 through a port 33 which is adapted to be closed by the valve 34. 95

In Fig. 2 all of the valves are shown closed and the bellows is shown to be somewhat collapsed. In normal positions, when the chambers 6 and 26 are at atmospheric pressure, the diaphragm is more or less taut, 100 being extended by the weight 35 and the member 27 occupies a lower position than that shown in the drawings with the valve 34 off its seat in the chamber 7', which communicates with the passageway 7. 105

The weight 35 is attached to the pressure responsive member 27 by a screw threaded rod 36 which is rotatable by the flattened end or handle 37. The rod is supported in eye-bolts 38 and 39, fore and aft, and when the 110 screw 36 is turned by the handle 37 the weight is thereby moved outwardly of the

hinge or inwardly towards the hinge to increase the effect of the weight upon the bellows structure.

It will be manifest that with a given suction effect the structure 25 will maintain the valve 34 closed to a greater extent when the weight 35 is nearer the hinge 28, and to a lesser extent when it is moved outwardly on the rod 36.

10 The valve 34 is mounted upon a stem 40 around which is an open spring 41 by means of which the valve is yieldingly self adjusting upon the port 33.

The pump for producing the air attenuation or movement necessary for the operation of the motor is connected to an opening 43 made in the side of the casing 5. The opening 43 is an outlet to the casing 5 and the pipe 44 is an air inlet.

15 20 While I have herein shown a single embodiment of my invention for the purpose of clear disclosure, it will be manifest to persons skilled in the art that considerable change may be made in the general arrangement and configuration of the parts 25 within the scope of the appended claim.

Having described my invention what I claim as new and desire to secure by Letters Patent, is:—

A device of the character described comprising a casing providing an elongated, horizontal air chamber of which a bellows chamber forms an aligning part, and two parallel vertical air passageways normally connecting said elongated horizontal air chambers; manual valves controlling said vertical passageways; in combination with a bellows enclosing a chamber constituting one part of one of said horizontal air chambers; a lever extending into the other aligning part of said air chamber and secured to the motive part of said bellows; a poppet valve operable thereby for controlling one of said vertical air passageways whereby said lever lifts said valve when the bellows is extended and closes the valve when it is collapsed and a weight adjustable longitudinally of the movable part of the bellows structure.

15 20 25 In testimony whereof I hereunto subscribed my name.

WILLIAM C. COLLIGNON.
